(57) **CLAIM**

The ornamental design for a power tool, as shown and described.

DESCRIPTION

FIG. 1 is a top side perspective view of a power tool showing our new design;

FIG. 2 is a bottom side perspective view of the power tool of FIG. 1;

FIG. 3 is a front elevational view of the power tool of FIG. 1;

FIG. 4 is a rear elevational view of the power tool of FIG. 1;

FIG. 5 is a left side elevational view of the power tool of FIG. 1;

FIG. 6 is a right side elevational view of the power tool of FIG. 1;

FIG. 7 is a top plan view of the power tool of FIG. 1; and, FIG. 8 is a bottom plan view of the power tool of FIG. 1. The broken lines shown in the drawings illustrate portions of the power tool that form no part of the claimed design.

1 Claim, 8 Drawing Sheets
